UNITED STATES PATENT OFFICE

92,565

DESIGN FOR A LUNCH ROOM KITCHEN CABINET

Jacob C. Stedman, Memphis, Tenn.

Application April 12, 1933, Serial No. 47,768

Term of patent 14 years

To all whom it may concern:

Be it known that I, JACOB C. STEDMAN, a citizen of the United States, residing at Memphis, Shelby County, State of Tennessee, have invented a new, original, and ornamental Design for a Lunch Room Kitchen Cabinet, of which the following is a specification, reference being had to the accompanying drawing, forming part thereof.

Fig. 2, a perspective view of the article, showing my new design, and

Fig. 3, a plan view of the same.

I claim:

The ornamental design for a lunch room kitchen cabinet as shown.

JACOB C. STEDMAN.
